Inventor,

Cyrus W. Jackson,

By Joseph A. Minturn
Attorney.

UNITED STATES PATENT OFFICE.

CYRUS W. JACKSON, OF INDIANAPOLIS, INDIANA, ASSIGNOR OF ONE-HALF TO JOSEPH A. MINTURN, OF INDIANAPOLIS, INDIANA.

MUSH-PACKAGE.

No. 834,474.

Specification of Letters Patent. Patented Oct. 30, 1906.

Original application filed December 23, 1903, Serial No. 183,283. Divided and this application filed October 17, 1904, Serial No. 228,877.

To all whom it may concern:

Be it known that I, CYRUS W. JACKSON, a citizen of the United States, residing at Indianapolis, in the county of Marion and State of Indiana, have invented certain new and useful Improvements in Mush-Packages, of which the following is a specification.

This application for patent is a division of my former application for patent for process 10 for making mush, which was patented in the United States November 29, 1906, No. 776,471, and from which the part embodied in this application was required to be eliminated by order of the Commissioner of Patents.

This invention relates to the manner in which the mush product of the process above referred to is prepared in suitable wrapped packages or rolls for commercial handling.

20. Mush has been sold in bulk in open pans like the ordinary bread-pans and was sliced off and removed by the retailer in quantities desired by the purchaser. This was disagreeable to the dealer, because of the wet and 25 sticky nature of the article which he had to handle in taking it out of the pan and wrapping it, and this operation was unpalatable to the customer. Moreover, the large open area of the pan furnished a catchall for impurities that would fall therein and render 30 the food unwholesome and uninviting to a fastidious taste, and it also exposed a large area of the goods to the atmosphere, causing the formation of a thick leathery skin by the 35 drying and other atmospheric action, which was ruinous to the mush as a food and soon made it unmerchantable.

This invention is a new article of manufacture which has been demonstrated to be 40 suitable for commercial purposes and which has met with an extended sale wherever it has been offered to the public. The mush molded in molds for which I have made application for patent in cylindrical rolls of approximately 45 three inches in diameter and eight inches long and weighing two pounds, the retail value of which is five cents, is of convenient size and shape for handling in a commercial way, and it is kept from drying out and the formation of a skin on the sides is prevented by wrapping the roll first in a waxed or paraffin-coated paper impervious

to moisture and not dissolvable therein, and this I reinforce and keep clean by wrapping the wax-covered roll in a wrapper of Manila 55 or other strong paper on which the label and directions for using may be impressed.

Referring to the accompanying drawings, Figure 1 represents the Manila wrapper, the wax sheet laid thereon, and the mush-roll 60 laid upon the wax sheet. Fig. 2 represents the mush roll wrapped in the wax sheet with the sheet partially turned in over the end of the roll; and Fig. 3 shows the roll of mush with both wax and Manila wrappers and the 65 fold of the latter at the end of the roll only partially completed to illustrate the manner of making said end fold. This view shows the two wrappers broken away in part to show both and also to show the roll of mush 70 within the wrappings.

A represents the cylindrical roll of mush which is preferably made in accordance with the formula set out in my above-mentioned application, of which this is a division, and 75 which is consequently of a firmer and more elastic nature than mush as ordinarily made, but is still largely water, being from four to five parts water to one of cereal, and consequently of a moist nature and susceptible to 80 deterioration by exposure to the direct action of the air.

B is the first or inside covering of wax paper. For purposes of economy and also to facilitate the wrapping and removal of this 85 covering I prefer to make the sheet only but little wider than the length of the roll of mush, so that the edges b will be turned only a little way over the end of the roll to stiffen the package at the corners and protect the 90 outside wrapper there more effectually on account of the fact that those edges will be subject naturally to the greatest wearing strain.

C is the Manila outside wrapper and is 95 wide enough to provide end folds c, that will overlap each other across the end of the roll from opposite sides of the roll, and because of the extra protection which these numerous layers of the wrapper provide at the ends of the roll the latter is amply protected without the wax-paper inner cover. The stiffness of the wrapper is ample to cause the folds to lie close enough to the roll without

being fastened, to protect the roll against mutilation by ordinary handling, but not to exclude the air.

Having thus fully described my invention, 5 what I claim as new, and wish to secure by Letters Patent, is—

As a new article of manufacture, a mush-roll package, the principal ingredients of the roll being ground cereal and water cooked 10 together, a wax paper covering the sides of the roll and folded partly over the ends of the roll to stiffen the package at its corners but not covering the major area of the ends,

and an outer wrapper of strong paper covering the sides of the wax-paper-covered roll 15 and folded in several layers across the ends of the roll completely covering said ends in a loose manner to admit air.

In witness whereof I have hereunto set my hand and seal, at Indianapolis, Indiana, this 20 3d day of October, A. D. 1904.

CYRUS W. JACKSON. [L. s.]
